COMBINED SQUEEZE BOTTLE AND DISPENSING CLOSURE

Thaddeus I. Kingsford, 3215 Embry Circle,
Chamblee, Ga. 30005

Filed Apr. 27, 1967, Ser. No. 6,859

Term of patent 14 years

(Cl. D9—2)

FIG.1

FIG.2

FIG.3

FIG.4

FIGURE 1 is a front elevational view of a combined squeeze bottle and dispensing closure showing my new design;

FIGURE 2 is a side elevational view with the dispensing control valve in an extended open position;

FIGURE 3 is a top plan view; and

FIGURE 4 is a bottom plan view thereof.

I claim:

The ornamental design for a combined squeeze bottle and dispensing closure, as shown.
